UNITED STATES PATENT OFFICE.

SAMUEL TROOD, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

ELECTRICAL CONNECTING DEVICE.

1,202,923.

Specification of Letters Patent. Patented Oct. 31, 1916.

Application filed March 1, 1913. Serial No. 751,429.

To all whom it may concern:

Be it known that I, SAMUEL TROOD, a citizen of the United States, and a resident of Edgewood Park, in the county of Allegheny and State of Pennsylvania, have invented a new and useful Improvement in Electrical Connecting Devices, of which the following is a specification.

My invention relates to electrical connecting devices and it has special reference to plug and socket connectors, such as are employed for sad irons, electric heaters and the like.

One object of my invention is to provide an electrical connector embodying means adapted to prevent unexpected interruption of the circuit, as from an accidental pull on the connector.

Another object of my invention is to provide a connector which shall be inexpensive and compact in construction and pleasing in appearance.

Heretofore, in the case of many plug-and-socket connectors, an accidental pull on the cord or the connector separated the contact members and thereby interrupted the circuit. According to my invention, I provide a peculiar construction which serves to lock the contact members in closed position when the cord or connector is pulled, and, consequently, the circuit cannot be accidentally interrupted. However, a simple means is provided for breaking contact when required.

In the accompanying drawing, Figure 1 is a longitudinal section of a connector embodying my invention. Fig. 2 is a section on the line II-II of the Fig. 1, showing the construction of parts and the electrical connections; and Fig. 3 is a longitudinal section of a modification of my invention.

Referring to the drawing, a plug connector 1 consists of a stationary post 2, provided with a bulbous head 3 and preferably connected to a load circuit; and a socket member 4 having parts engaging the head 3 and preferably connected to the supply circuit. The post 2 may be cylindrical, as shown, or of any other suitable form, and is attached to a base 5 in any convenient position from which it is spaced by suitable insulating pieces 5a.

The member 4 of the connector comprises an outer cylindrical casing 6 of insulating

material and an inner shell 7 of conducting material, the interiorly thickened lower end of which is shaped to form a relatively small tubular surface 8 and an inverted frusto-conical extension surface 8a. A removable cap 9 slidably engages the outer end 6a of the casing 6, and a forked clip 10, adapted for engagement with the head 3, has its closed end 11 held within the cap 9 and its forked end in proximity to the surfaces 8a. A helical compression spring 12 acts between the upper end of the shell 7 and a ring member 12a that engages the forked clip 10 at its junction point, for keeping the parts of said clip within predetermined limits of position. The spring 12 is electrically connected to both the shell 7 and the clip 10 and serves to clamp said clip between the head 3 and the surface 8a. A supply conductor 13 projects through a bushing 14, seated in one side of the casing 6, and is connected to the shell 7, and, consequently, to the clip 10, by means of a ring 15.

Assuming the connector to be in the position shown in Fig. 1, to open the circuit, the cap 9 is raised to break the contact of the clip 10 with the head 3 of the post 2, when the casing 6 may be removed, thus completely separating the clip from the post. However, if the supply conductor 13 or the casing 6 is pulled when the connector is in closed position, the contact in said connector will not be broken because the wedging surface 8a will grip the forked clip 10 and thus prevent it from expanding sufficiently to pass over the head 3 of the post 2.

Reference may now be had to Fig. 3, in which a modified form of the socket member 4 is employed in coöperation with the stationary terminal post 2. The socket member comprises an insulating casing 16, an associated clamping member 17 and a contact member 18 having a bifurcated contact end 22. The casing 16 of non-conducting material may be of any suitable form and its top wall 19 may be provided with a threaded opening 20 to receive a conducting bushing 21. The clamping member 17 is provided with an inverted frusto-conical interior surface 8a for locking the contact members in closed position in the manner set forth in connection with Fig. 1, and the said member is screwed into the casing 16.

or is attached thereto in any other suitable manner. The outer end 23 of the member 18 is screwed into an opening 24 in the conducting bushing 21 and is provided with a 5 suitable external knob or head 25 of insulating material. The supply conductor 13 is attached to the bushing 21 or is electrically connected to the member 18 in any other suitable manner.

10 It will be understood that the clamping action of the connector shown in Fig. 3 is identical with that of the connector of Fig. 1. The process of making or breaking contact, however, is different. Assuming the 15 connector to be in the closed position shown in Fig. 3, the process of breaking contact involves a turning and upward movement of the member 18 by means of the knob 25 and the threaded portion 23 until said member has moved completely out of contact with the head 3.

I do not wish to be restricted to the specific structure and details herein set forth, but desire that only such limitations 25 shall be imposed as are indicated in the following claims.

I claim as my invention:

1. An electrical connector comprising relatively movable coöperating contact members, a supporting means for one of the said members, means dependent upon an initial movement of the said supporting means for forcing the said members into locking engagement and means movable independently 35 of the supporting means for disengaging the said members when it is moved outwardly.

2. An electrical connector comprising a stationary contact member, a movable contact member having a plurality of resilient 40 parts, a supporting member for the movable contact member having an inwardly inclined surface for engaging the said parts under predetermined conditions and means interposed between the said parts and the supporting member for disengaging the said contact members when it is moved outwardly.

3. In an electrical connector, the combination with relatively movable coöperating contact members, of means for resiliently supporting one of said members, means associated with said supporting means and dependent upon an initial movement thereof for preventing disengagement 55 of said contact members, and means movable independently of said supporting means, for disengaging said members.

4. In an electrical connector, the combination with relatively movable coöperating contact members, of an incasing socket 60 for supporting one of said members, a yielding connector interposed between the said member and its socket, wedging means constituting one portion of said socket and dependent upon an initial movement thereof

for preventing disengagement of said contact members, and means movable independently of said socket, for disengaging said members.

5. An electrical connector comprising a 70 supporting member having an inwardly inclined surface, a resilient movable contact member disposed entirely within the supporting member but normally out of engagement with its inclined surface, a 75 coöperating stationary contact member adapted to cause the resilient contact member to engage the inclined surface to retain the contact members in operative engagement, and means for effecting disengagement 80 of the contact members when it is moved outwardly.

6. An electrical connector comprising a stationary contact member having a bulbous portion, a resilient movable contact member, a supporting member for the movable contact member having an inclined inner surface, said movable contact member being disposed entirely within the supporting member but normally out of engagement 90 with its inclined surface, means associated with the supporting member for effecting engagement between the inclined surface and the movable contact member when the bulbous portion of the stationary contact member is engaged by the movable contact member, and means for effecting disengagement 95 of the contact members when it is moved outwardly.

7. An electrical connector comprising a 100 stationary contact member having a bulbous portion, a resilient movable contact member, a supporting member for the movable contact member having an inclined inner surface, said movable contact member being disposed entirely within the supporting member but normally out of engagement 105 with its inclined surface, resilient means for causing the movable contact member to engage the inclined surface under predetermined conditions to effectively grip the bulbous portion of the stationary contact member, and means for effecting disengagement 110 of the contact members when it is moved outwardly.

8. In an electrical connector, the combination with a stationary contact member and a coöperating movable contact member, of an incasing socket for supporting the movable member and having a portion normally out of engagement with the movable member for coöperating with the contact members only when they are in engagement, means associated with the said socket for maintaining a predetermined pressure between the said contact members, and means for effecting disengagement of the contact members when it is moved outwardly.

9. In an electrical connector, the combination with a stationary contact member 120

and a coöperating movable contact member, of an incasing socket having a wedge-shaped surface normally out of engagement with the movable contact member and adapted to force the said contact members into engagement with each other, resilient means associated with the said socket for maintaining a predetermined pressure between the said contact members, and means

for effecting disengagement of the contact members when it is moved outwardly.

In testimony whereof, I have hereunto subscribed my name this 18th day of February, 1913.

SAMUEL TROOD.
